GYRATING TOY

Karl Arnold, Nuremberg, Germany

Application May 8, 1935, Serial No. 20,390
In Germany January 12, 1935

5 Claims. (Cl. 46—47)

Gyrating toys are already known which, during the gyration form a united whole but which always are of the same configuration. These toys are monotonous and consequently do not fulfil the 5 object of a toy.

The invention relates to a toy which likewise appears as a closed structure when rotating, but the configuration of which continually changes owing to the shifting of link chains and holding 10 means.

An embodiment of the invention is illustrated in the accompanying drawing in which:—

Fig. 1 shows the toy in side elevation, the link chain being omitted on one side.

15 Fig. 2 shows a portion of the link chain in front elevation.

Fig. 3 is a top plan view of the shifting and holding plate.

A rack and pinion drive mechanism *a* with 20 turn spring adapted to be periodically driven drives a shaft *b* carrying at its lower end a shift-able plate *d*, the ends *c* of which are bent upwards inclined towards the shaft and rolled in-wards at their extremities. A plate *g* having 25 downwardly bent ends *h* with inwardly rolled extremities and carrying an apertured disc *f* of adhesive material, such as rubber, is shiftably mounted on the upper end of shaft *b*. The ends *c* and *h* of the plates *d* and *g* are connected by 30 chains formed of brightly painted sheet metal links *i* held together by wire links *k*. By exerting pressure on the rack of the driving mecha-nism the shaft *b* and consequently the plates *d* and *g* and the chains attached thereto gyrate, 35 the individual links of the chains being thrown outwards by centrifugal force to form a con-figuration which can be continually changed by shifting one or both of the plates *g* and *d* up-wards or downwards on the shaft *b* so that the 40 chains are stretched or slackened and a larger or smaller configuration will be formed, the width of which is dependent upon the number of links in the chains. To enable larger and smaller con-figurations to be changed to form other novel 45 configurations several bars or plates *n* having apertures *m* for the passage of the chain links and carrying each one an apertured rubber disc *l* are shiftably mounted on the shaft *b*. By shift-ing these bars upwards or downwards on the 50 shaft the configuration produced is again changed. Thus, for example, with two shiftable plates *n* it is possible to produce many different figures. A sleeve *o* is slipped on to the upper ex-tremity of the shaft *b* and carries a flat wire 55 spiral *p*. On the end of this spiral toy figures

q are suspended. If the shaft *b* is rotated, the toy figures will be swung outwards and describe a circle. At the same time by varying the pres-ure exerted on the rack, the wire spiral will spread and contract so that the size of the circle 6 described by the figures can be changed.

Without departing from the scope of the in-vention large and small wires slideable on the shaft and adapted to engage in eyes in the sheet metal chain may be employed instead of the 10 plates *n* for changing the shape of the configura-tion produced during the gyration. The links of the chain may be made of other material than sheet metal, and may be of different shape and inter-connected in a different manner to that 15 shown in the drawing. Finally, some other driv-ing mechanism may be employed instead of a rack and pinion driving mechanism.

I claim:—

1. A gyrating toy, comprising in combination 20 a driving shaft, two plates shiftable on and ro-tatable with said shaft, a driving mechanism adapted to rotate said shaft, bent over ends on said plates, and chains composed of separate links connecting said bent over ends and adapted 25 to swing out under centrifugal force during the rotation of said shaft to simulate a solid con-figuration.

2. A gyrating toy as specified in claim 1, in 30 which the plates are displaceable on said shaft to vary the configuration formed by the chains.

3. In a gyrating toy as specified in claim 1, bars each provided with a rubber ring displace-ably secured on the shaft between the plates and engaging said chains at an intermediate 35 point of their length and adapted to vary the configuration produced by said chains.

4. In a gyrating toy as specified in claim 1, bars each provided with a rubber ring displace-ably secured on the shaft between the plates 40 and provided with apertures surrounding said chains at an intermediate point of their length and adapted to vary the configuration produced by said chains.

5. In a gyrating toy as specified in claim 1, 45 a sleeve slipped on the free end of the shaft, a flat wire spiral fixed on said sleeve and adapted to expand under the action of the centrifugal force according to the speed of rotation of said shaft, and toy figures detachably suspended from 50 said spiral spring and adapted to swing out under the action of centrifugal force and describe a circle varying in diameter according to the speed of rotation and the expansion of said spring.

KARL ARNOLD. 55
